Naho Tannaka.

UNITED STATES PATENT OFFICE.

NAHO TANAKA, OF BOSTON, MASSACHUSETTS.

TELEPHONE-TRANSMITTER.

1,252,057.

Specification of Letters Patent. Patented Jan. 1, 1918.

Application filed February 14, 1917. Serial No. 148,496.

To all whom it may concern:

Be it known that I, NAHO TANAKA, a subject of the Emperor of Japan, residing at Boston, in the county of Suffolk and Commonwealth of Massachusetts, have invented new and useful Improvements in Telephone-Transmitters, of which the following is a specification.

This invention relates to improvements in telephone transmitting apparatus, in which the entire working parts are yieldingly separated from their casing or stationary support, at least in the direction in which the diaphragm is destined to vibrate, so that 10 the working parts are movable relatively to the casing in that direction, though within a minute or almost imperceptibly small limit. Although apparently for insulating and damping purposes, certain ordinary 15 transmitters are provided with some separating means around the diaphragm. In the present invention, cushioning means are employed not only around the diaphragm periphery, but also the back part or unit is 20 independently cushioned against the casing, in a rigidity sense, entirely or substantially insulating the entire working parts from the latter, and preferably, similar provision is 25 further employed for connecting the front and back parts. In addition to an usual 30 (mica) auxiliary diaphragm or a flexible sheeting, so that the front and back units and the casing are separated by cushions, one from the others. In operation, by 35 proper adjustment of pressure thereon, these provisions of cushions seem to shift the current variation nearer to a sinusoidal form by modifying the magnitude of the increment and the decrement of the carbon cell 40 resistance.

The chief objects of this invention are to provide apparatus in which sound, particularly voice, is translated into such electrical impulses that tend to produce sound at least 45 of clear soft tone, without accompanying disagreeable harsh sound, or to transmit sound without distortion that seems to be inherent to the nowaday telephones, as far as the transmitting apparatus is concerned; 50 first by applying my invention to my multiple carbon cell transmitter in which the resistance variability is at the same time increased, when the cells are connected in series, more in higher resistance circuits; sec-

ond, by introducing this invention to ordinary transmitters of solid back type, viz., by a simple addition of parts thereto without discarding the original parts, so that ordinary pieces of apparatus may be easily convertible into the new type with a very little 55 additional outlay. I attain to the above objects by constructing apparatus as herein shown and described.

With the above and other objects in view, this invention comprises certain detail of 60 construction and arrangements of parts, as will be hereinafter more fully described, illustrated and claimed.

The invention will be best understood from the following description taken in connection with the accompanying drawings, forming a part of this specification, in which similar numerals of reference indicate similar or corresponding parts throughout the 70 several views, and in which—

Figure 1 is a vertical central section, partly in elevation, of a multi-cell transmitter embodying my invention; Fig. 2, a partly broken back view of the same, illustrating the inner structure; Fig. 3, a vertical 75 central section of a transmitter, similarly embodying this invention, as applied to a transmitter of solid back type; and Fig. 4, a broken back view of the above.

Referring to Figs. 1 and 2, 1 designates a 80 front plate which has two edged rings 2 and 3. The front ring 2 attached thereto at the rear face, or preferably the front plate is shaped to form the front ring, and the back ring 3 through its flanges (which may be 85 flexible) is attached to the front plate by means of screws, but the latter ring may be attached to a back support or bridge which will be referred to later. To be sure, the front plate has an opening to receive a cus- 90 tomary mouth-piece.

Disposed between the rings 2 and 3, a diaphragm or vibrator 4 carries a rubber (or the like) collar or cushions 5 at its peripheral portion, the rings compressingly or 100 compressively holding the diaphragm through the cushions.

By means of screws 6, having small or light shanks 7 and nuts 8, front electrodes 9 being plated and soldered to the shanks are 105 secured to the diaphragm 4 as shown, constituting a vibratory unit or part.

At the rear of the front plate 1, a bridge

or support 10 is yieldingly or elastically attached thereto through cushioning washers or pads 11, such as of felt or soft rubber, which are held together under pressure with the support between the edge of the front plate and guard pieces 12 by screws 13 which pass loosely through holes of the support 10, or through bushings 14 provided in the holes. (See Fig. 4.)

10. Adjustably attached to the support or bridge by an usual screw means, a plurally cup-shaped piece 15 bears insulated back electrodes 16 at the cup bottoms, forming a back unit or part.

15. Covering the mouths of the cups, a flexible sheeting 17 is secured between the cup piece 15 and a guard plate 18 the latter having perforations which coincide with the cup mouths. The sheeting and the vibratory unit are yieldingly connected through ring cushions 19, such as of felt or soft rubber, which are held together with the sheeting between the shanks 7 and the back nuts 8, the screw stems 6 passing through the perforations of the sheeting and the cushions, and are disposed in such manner that each pair of the front and back electrodes confront in parallel within a closed chamber formed thereby. Variable resistance mediums or 30 granular carbon 20 are placed in the chambers.

The carbon cells thus formed are joined preferably in series, either by insulating one of the front electrodes from the diaphragm, or employing a diaphragm of suitable insulating material.

In Figs. 3 and 4, a bridge 10, which corresponds to the support 10 of Figs. 1 and 2, is similarly cushioned by yielding washers or 40 pads 11 at the ends thereof. The bridge carries a cup or case 21 which contains a back electrode 16 and granular carbon 20, said cup and electrode forming a back unit. A diaphragm 4 at the front thereof has a rubber band collar 5 and is pressed by customary damping springs with yielding pads (not shown) against a front plate 1, and a front electrode 9 is mounted on the diaphragm as before, constituting a vibratory 50 unit. These two units are connected by a sheeting 17 and washers 19 in a similar manner previously described referring to Figs. 1 and 2.

I wish to have it understood that the construction and arrangement of parts shown in 55 or described for one form is similarly applicable to the other.

From the foregoing description taken in connection with the accompanying drawings, the advantage of the construction and the arrangements of parts and the method of operation will be readily apparent to those skilled in the art to which this invention appertains, and while I have herein set 65 forth the invention in what is now thought

to be the best embodiments thereof, I wish to have it understood that the apparatus herein shown and described are merely illustrative, and that therefore I do not confine myself to any strict conformity to the showing of the drawings, but such changes or modifications may be made, when desired, as to fall or come within the scope of the invention as claimed.

Having thus described the invention, what 75 I claim is:—

1. In a telephone transmitter, the combination with a casing; of front and back electrodes bearing units, cushions between the casing and the said two units, the units 80 being independently attached to the casing through the cushions, and parts constituting therewith a variable resistance device.

2. In a telephone transmitter, a yielding mounting for the working parts thereof, 85 comprising a casing, a back support, and cushions separately held between the working parts and the casing, and between the back support and the casing, the working parts and the supports being independently 90 attached to the casing.

3. In a telephone transmitter, the combination with a casing, a vibratory unit, a back unit elastically separated from the vibratory unit, and granular carbon between 95 the units; of two sets of cushions, each set separating one of the said two units from the casing which holds the said units separately through the cushions.

4. In a telephone transmitter, a casing, a 100 diaphragm attached to the casing, a variable resistance combination connected to the diaphragm, cushion means, and a rigid support holding the said resistance combination and attached to the casing through the 105 cushioning means independently of the diaphragm.

5. In a telephonic apparatus, the combination with a casing, a variable resistance unit comprising front and back electrode 110 bearing elements and granular carbon; of elastically mounting means for the resistance unit, provided between the casing and the front electrode bearing element, and between the casing and the back electrode 115 bearing element, the electrode elements being held thereby, each independently of the other.

6. A telephone transmitter, provided with a casing, a vibrator held by the casing, cushions, a back unit elastically separated from the vibrator and yieldingly attached to the casing through the cushions, independently of the vibrator, and variable resistance material between the vibrator and the back 125 unit.

7. A telephone transmitter, provided with a casing, a vibratory unit, a back unit, and cushions between every pair of the above parts, the said vibratory and back units 130

being elastically attached to the casing independently, one of the other.

8. In a telephone transmitter, the combination with a casing, vibratory and back units elastically connected together and having a variable resistance medium therebetween; of cushions disposed and separately held between the said units and the casing, so as to permit the units to move relatively 10 to the casing, at least, in the direction in which the vibratory unit is destined to vibrate.

9. A telephone transmitter, provided with a casing, front and back electrode bearers, 15 granular carbon, a sheeting attached to one of the said electrode bearers and yieldingly connected to the other bearer, and cushions which separate the said electrode bearers from the casing, the casing separately holding 20 the bearers through the cushions.

10. In a telephonic apparatus, the combination with a casing, a vibratory unit, a back unit, and granular carbon between the units; of a flexible sheeting attached to one 25 of the said units, cushions held together with the sheeting by the other unit, and other cushions through which the said units are independently attached to the casing.

11. In a telephone transmitter, a casing, 30 a diaphragm, cushions for the diaphragm, a variable resistance unit coöperatively related to the diaphragm, a support for the said resistance unit, holding means for the support adjustably attached to the casing, 35 and other cushions between the support and the said means, the said two sets of the cushions being separately held by the casing under pressure.

12. In a variable resistance device, a casing, 40 a diaphragm, a front padding through which the diaphragm is held by the casing, a back support, a back padding disposed on opposite sides of the support, screw means adapted to engage with the casing for holding 45 the support and the last mentioned padding together separately from the diaphragm, and variable resistance mediums coöperatively related thereto.

13. A telephone transmitter, provided with 50 a vibratory part having a cushioned diaphragm, a casing having projections for holding the diaphragm, a back part, and cushions for the back part held therewith together by the casing separately from the 55 diaphragm.

14. A telephone transmitter, provided with a casing, a vibrator, a cushioning element, a back part held by the casing and elastically attached to the vibrator, projecting 60 members held in the casing and holding the vibrator and the cushioning element together, the projecting members being shaped and relating to the cushioning element in such manner, that comparatively small part 65 of the latter is effectually under pressure,

and a variable resistance medium in coöperative relation thereto.

15. In a telephone transmitting apparatus, front and back electrode bearers, a casing having edged projections, and cushions for 70 the electrode bearers, one of the bearers being held by the said edged projections, and the other attached to the casing, each through its cushions.

16. In a telephone transmitter, the combination of a casing and a diaphragm, projections from one of the said elements, cushions over the edges of the projections in pressure contact therewith, a support and a mounting yieldingly connecting the support to the casing independently of the said 80 cushions; with a variable resistance unit.

17. In a telephone transmitter, a cushioned diaphragm, a casing having projections in contact with the cushion of the diaphragm, elastically pressing means which coöperate with the projections in holding the diaphragm compressively therebetween, a back support, a padding separating the support from the casing, and variable 90 resistance means in coöperative relation thereto.

18. In a telephone transmitter, the combination of a casing having edged rings, a cushioned diaphragm held between the rings, a back unit, a support for the back 95 unit, and a cushion mounting for the support, held therewith together under pressure by the casing and its attachments; with parts constituting therewith a variable 100 resistance device.

19. A telephone apparatus, provided with a yielding mounting for the vibratory part thereof, comprising a back part, a sheeting yieldingly connected to one of the said two parts and rigidly to the other, a casing holding the back part, cushions on opposite sides of the vibratory part, and members having narrow edges for holding the vibratory part through the cushions.

20. A telephone transmitter, provided 110 with a casing having a projection or shoulder which terminates with a narrow edge, pressing means attached to the casing, a cushioned diaphragm held between the said means and the projection or shoulder, 115 cushioning means, a support attached to the casing through the said cushioning means, and a variable resistance medium coöperatively related thereto.

21. In a telephone transmitter, a casing, 120 a vibratory unit elastically held thereby, a support yieldingly attached to the casing, a back unit held by the support, cushions, and a flexible sheeting attached to one of the said two units, which has cups or cases 125 containing electrodes and granular carbon, and yieldingly connected to the other unit through the cushions.

22. In a telephone transmitter, a casing, 130 a vibratory unit cushioned against the cas-

ing and held thereby, cushioning washers,
a back unit elastically mounted on the cas-
ing through the washers, a carbon contain-
ing case carried by one of the said two units,
5 a sheeting attached to the case, and pads held
together with the sheeting by the other of
the said units.

In testimony whereof I affix my signature
in presence of two subscribing witnesses.
